(57) **CLAIM**

The ornamental design for a nail polisher, as shown and described.

DESCRIPTION

FIG. 1 is a front elevational view of a nail polisher showing my new design;

FIG. 2 is a rear elevational view thereof;

FIG. 3 is a bottom plan view thereof;

FIG. 4 is a top plan view thereof;

FIG. 5 is a right side view thereof;

FIG. 6 is a left side view thereof;

FIG. 7 is an enlarged view of portion "7" shown in FIG. 1;

FIG. 8 is an enlarged view of portion "8" shown in FIG. 5;

FIG. 9 is a perspective view thereof; and,

FIG. 10 is another perspective view thereof.

The broken lines in FIGS. 4 and 10 illustrate portions of the article which form no part of the claimed design. The remaining broken lines in the drawings illustrate enlarged view indicators which form no part of the claimed design.

1 Claim, 7 Drawing Sheets
